ROOF VENTILATOR

Jay P. Johnson, Euclid, Ohio, assignor to The Swartwout Company, Cleveland, Ohio, a corporation of Ohio

Application March 17, 1953, Serial No. 342,796

17 Claims. (Cl. 98—42)

This invention relates to ventilators and more particularly to improvements in gravity roof ventilators of the multiple type.

In the design and construction of multiple gravity roof ventilators one problem that has persistently resisted solution prior to my invention has been that of reducing the height of the ventilator in relation to the width of the throat opening without sacrificing ventilating efficiency, weatherproofness, cost, or the ratio of net to gross area of opening. My invention not only solves this problem but enhances the aerodynamic efficiency and weatherproofness of the ventilator, reduces weight and cost of manufacture, installation and upkeep, facilitates splicing multiple units, gives better access for painting and cleaning, improves drainage and minimizes the tendency of debris to accumulate to impair drainage or other desirable functions of the ventilator.

The objects of my invention include the solution of the problems and the procurement of the advantages stated above.

It is thus an object of my invention to reduce the height of the ventilator in respect to the throat opening and increase the aerodynamic efficiency as, for example, by permitting air moving through the ventilator to make fewer and less abrupt turns and have a freer path of flow without loss of weatherproofness. It is a further object of the invention to provide a gravity roof ventilator in which virtually all of the top area of the ventilator and particularly those portions overlying the bottom gutters are open to workmen servicing the ventilator, thereby permitting them to use brooms and like means to remove leaves, nests, insects, dead birds and other debris. It is a further object of the invention to provide a gravity roof ventilator which can be built and maintained with a minimum of material, weight, labor and cost.

Another object is to increase the exhaust area of the ventilator with reduction in height and increased freedom of air movement and enhanced weatherproofness. Another object is to provide an improved curb flashing and supporting structure and relationship between the curb and the ventilator body, and to facilitate splicing multiple units with respect to the curb flashing and supporting structure. Another object is to improve the structure and operation of the ventilator dampers and operating mechanism in themselves and in relation to the whole ventilator.

It is a further object of the invention to provide a gravity roof ventilator provided with end caps of novel design. Preferably such end caps are of bulged shape and constructed in two parts. One of these is a stationary upper part and the other is a movable lower part that is held in place by quick detachable means in a manner permitting ready access to the interior end wall structure. In a gravity roof ventilator of reduced height of the kind to which the invention relates, the use of such end caps, particularly if the curb forming part of the supporting structure is located interiorly of the end and side-wall structure of the ventilator, not only provides easy access

2

to the interior but greatly facilitates the discharge of rain water at the ends of the ventilator.

Other objects and advantages of the invention will be apparent from the description which follows and from the accompanying drawings.

In the drawings,

Figure 1 is an isometric view of a gravity roof ventilator of the multiple type incorporating features and principles of my invention.

10 Figure 2 is an elevation on a reduced scale of the near end of the ventilator of Figure 1 as it appears after removal of the end cap, certain parts such as the means for moving the damper actuating bar being omitted in the interest of clarity.

15 Figure 3 is a partially exploded view of the center portion of Figure 2, the splash shield being omitted to show details of construction.

20 Figure 4 is a perspective view showing a pair of panel braces of Figure 3 with their attaching and reinforcing flanges in their working relation to each other but without other elements such as gutters, deflecting means, etc.

25 Figure 5 is a simplified view partly in elevation and partly in section corresponding in a general way to the center portion of Figure 2, but on a larger scale and without background details.

30 Figure 6 is a fragmentary vertical section taken through the near end of the ventilator of Figure 1 in the plane of a damper axis and the line 6—6 of Figure 2, certain parts such as the damper and the damper actuating link being omitted.

Figure 7 is a fragmentary perspective showing the apron construction to receive the lower troughs, and

Figure 8 is a similar view showing the relation of apron, lower trough, main braces and partition.

35 As shown by way of illustration in Figure 1 of the drawings, the ventilator is adapted to be positioned and mounted on suitable supporting structure, the same comprising a flat roof 1 and a rectangular curb 2 extending upward from the plane of roof 1. Not appearing in Figure 1 but indicated in dotted lines in Figure 2 and more clearly shown in Figure 6 is a rectangular opening 3 defined by the curb 2 in the roof structure supporting the ventilator. The ventilator of Figure 1 is illustrative of a three-element multiple unit in which, in practicable commercial form, the throat of each element at the damper is about a foot wide and the ventilator has correlated gross external dimensions of approximately seven feet six inches in width from side to side across the near end, i. e., transverse the throats, approximately ten feet in length from the near corner to the far corner along the right-hand side of the ventilator as seen in Figure 1, and approximately two feet in height from the top of curb 2 to the top of the ventilator. The roof opening 3 measures approximately 7'0" by 9'4". Figure 1 is broken to foreshorten the length of the ventilator as viewed. A six-element multiple unit would be approximately fifteen feet "wide" and otherwise of the same dimensions as the three-element unit, covering a corresponding roof opening of greater "width." For consistent terminology the terms length and width are conveniently preserved in the reference to dimensions taken respectively in the direction of the long dimension, i. e., length, of the damper controlled throat opening of a single element and the width of the throat, albeit as the multiple of elements of the same length in a single ventilator increases the "width" of the whole integrated ventilator may much exceed the length thereof. Similarly I shall refer to the interior and exterior vertical walls or partitions of the elements, units and ventilators which extend parallel to the long dimensions of the throat openings as side walls and/or partitions and refer to the exterior walls that lie transversely of the long dimensions of the throats as end

40

45

50

70

walls. Efficiency and convenience of manufacture, handling and erection are well served when the primary unit of the ventilator comprises three elements whether employed alone as a complete ventilator as shown in Fig. 1 with two internal partition walls 6 and 7 and external side walls 5 and 8, Fig. 2, or made with one or both side walls or members corresponding to the partitions 6 and 7 for integration with similar or complementary units to form a whole ventilator of great width between but two external side walls 5 and 8 per se.

Surrounding curb 2 on all four sides thereof is a vertically disposed apron 4, the bottom of which terminates at its lower edge a few inches above the plane of roof 1, Figures 1, 2, 5 and 6. The apron 4 is mounted on but spaced (at least for tolerance) somewhat from curb 2 in the manner best shown in Figures 2 and 6, and is carried on the curb by angle irons 4a and secured to and/or spaced more or less from the exterior vertical face of the curb by studs or lag screws 4b and spacers 4c. Along the sides of the ventilator the apron 4 takes the form of a shallow rectangle with its upper edge underlying and supporting the half-troughs 16 and 17, Fig. 2, where, if desired, water may be spilled externally of the apron and between the apron and the spaced lower parts of the adjacent side walls 5 and 8. At each of the near and far ends of the ventilator unit the upper portion of apron 4 is characterized by generally trapezoidal upward extensions 11, 12 and 13, more fully described hereinafter, between and upon the sloping upper edges and flanges of which the lower troughs and half-troughs, 14-17 and main braces 31 and 32 are supported directly and substantially all of the ventilator structure supported indirectly. Apron 4 thus serves as a foundation and frame to support the ventilator as a whole, being itself supported by and secured to curb 2, and is appropriately made of relatively heavy gauge stock for this reason.

In the preferred form and embodiment of my invention shown in the drawings, there are four side walls in all, respectively designated 5, 6, 7 and 8. In a sense, intermediate side walls 6 and 7 may be regarded as partitions; however, as seen in Figure 2 they serve as the side walls for the ventilator element occupying the middle portion of the three-element unit. The end wall structure of the ventilator, shown to better advantage elsewhere in the drawings, is obscured in Figure 1 by end cap 9, of which there is one at each end of the ventilator. Thus the multiple ventilator unit shown in the drawings includes supporting structure having three throat openings therein, side wall structure forming three elements with substantially separate throats or ventilating channels over the opening 3 in the supporting structure, end wall structure cooperating with the side wall structure at the opposite ends of the three ventilating channels, and an end cap at each end of the ventilator. Roof 1 and curb 2 are of the type of material conventionally employed for such purposes; i. e., wood, concrete or the like. The sheet and sheet-like parts of the ventilator including the apron, the side wall structure, the end wall structure and the end caps are preferably made of galvanized sheet metal of appropriately different gauges.

It has been noted above that at the near and far ends of the ventilator the upper portion of apron 4 surrounding curb 2 has three generally trapezoidal extensions, designated 11, 12 and 13, Figures 2, 5 and 7. Such trapezoidal extensions are preferably formed integrally with the main portion of apron 4, which is preferably of unitary construction from one side of the ventilator to the other.

Collectively, trapezoidal extensions 11, 12 and 13 at the opposite end of the ventilator form the means for supporting two louver troughs or bottom gutters designated 14 and 15 which underlie intermediate side walls or partitions 6 and 7 in the manner shown in Figures 2, 3 and 5. As appears from Figure 5, there is considerable clearance between the bottoms of walls 6 and 7 and bottoms of the

troughs 14 and 15. This facilitates employment of the whole drainage capacity of each trough when water is largely entering it from only one side of the partition. This also promotes cleanliness, facilitates painting and eliminates the tendency of the parts to rust or debris to collect were they secured at the bottom of the trough. With particular reference to Figure 5, it will be noted that bottom gutters 14 and 15 may be considered as consisting of left-hand trough halves 14a and 15a and right-hand trough halves 14b and 15b.

Bottom gutters 14 and 15 extend longitudinally of the ventilator from one end thereof to the other, being lipped over at L and supported by the trapezoidal extensions on apron 4 and flanges, see Figs. 6, 7 and 8. As indicated also in Figures 2, 3 and 5, each trough half of each of the bottom gutters has a vertically extending and inturned flange along its upper edge as at 14c and 15c. As shown in Figure 3, these flanges not only define the throat of the ventilating channel but also stiffen and strengthen the troughs and half troughs and serve as the means for seating the dampers when the latter are in closed position.

The portion of the ventilator shown in section in Figure 5 is the middle element of the three parallel ventilating channels which the primary unit comprises. Trough halves 14b and 15a, together with the damper, collectively constitute fixed and movable means spanning the channel from one side to the other at the base of the side wall or partition structure. To the left of the ventilating channel shown in Figure 5 is a similar ventilating channel; to the right, a third ventilating channel constituting a mirror image of the one on the left-hand side. The relationship between them is apparent from Figure 2.

As shown in Figure 2, the left-hand ventilating channel or element is characterized by a trough half 16 supported by the left-hand end of trapezoidal extension 11 of apron 4, such trough half 16 corresponding generally to trough half 14b of bottom gutter 14 but terminating at or near the base of the side wall and overlying apron 4. Similarly, the ventilating channel on the right-hand side of the ventilator has a trough half 17 supported by trapezoidal extension 13. Trough half 17 corresponds in a general way to trough half 15a of bottom gutter 15, but, like trough half 16, terminates at or near the base of the slant and adjacent side wall and overlaps the apron 4. It is not without my teaching to make the trough halves 16 and 17 integral with or joined in integrated extension of the adjacent part of the apron 4. Trough halves 16 and 17 may be spaced, as shown at the left in Figure 2, as from side walls 5 to facilitate the discharge of rain water along the sides of the ventilator, or in the alternative, as shown at the right of Figure 2, may be carried outwardly and flanged downwardly and joined as to the side wall 8 to discharge essentially at the end of side wall 8 of the ventilator. Trough halves 16 and 17 are provided with flanged seating portions 16c and 17c for the dampers and, where they overlap the trapezoidal extensions 11 and 13 of apron 4, have overhanging and downwardly projecting lips L similar to those on bottom gutters 14 and 15, see Figs. 6, 7 and 8. The middle bottom portions of the gutters 14 and 15 and the equivalent portions of the half-gutters 16 and 17 are flattened to conserve height of the ventilator while retaining the liquid capacity of the gutters for carrying off rain and water.

Dampers 18 coact with the flanged seating portions 14c, 15c, 16c and 17c along the upper edges of all the trough halves. The manner in which the dampers operate is illustrated in Figures 2 and 5, in which middle damper 18 is shown in a position in which the throat of the ventilating channel is largely open. As indicated by the lower of the two dotted arrows, if the damper is moved in a counterclockwise direction about the axis of pivoted rod 19 on which it is mounted, flanged side portion 18a of the damper seats upon seating portion 14c of trough half 14b of bottom gutter 14; at the same time, flanged side portion 18b thereof seats upon, i. e.

in nested underlap of, seating portion 15c of trough half 15a of bottom gutter 15. The relationship of these parts when the dampers are in the fully closed position is shown in Figure 3. Preferably dampers 18 have a narrow central integral raised channel 18c overlying the axis 19 wherewith to dispose the main sheet of the damper in the plane of the axis and to give torsional stiffness to the damper. The channel 18c and the flanges 18a and 18b together strengthen the damper and give it longitudinal as well as torsional rigidity assuring its proper movement and uniform light and weather sealing action with the coacting flanges of the adjacent troughs.

Referring again to Figure 5, damper 18 is of the butterfly type, being pivoted for rotary movement through an arc of about 90°. Connected to damper rod 19 are two links 20 and 21, of which the latter is coupled to an actuating bar 22. Inasmuch as the illustrated ventilator unit has three ventilating channels in parallel, there are three dampers 18. All are preferably actuated from the same actuating bar 22 in the manner indicated in Figure 2. Actuating bar 22 is supported from apron 4 by a plurality of steady brackets 23, Figs. 5 and 6, carrying small rollers 23a, Fig. 6, upon which the bar 22 is freely slideable.

Rigidly fastened to actuating bar 22 is a traveling nut 24 which coats with the threaded shaft 25 shown in Figure 5. Threaded shaft 25 carries at its left-hand end a gear 26 which mates with a like gear 27 suitably coupled to a pulley, motor or the like. The latter is indicated by the circle 28 shown in dotted lines at the left-hand end of Figure 5. When gears 26 and 27 and threaded shaft 25 are rotated by pulley or motor 28, traveling nut 24 moves axially of threaded shaft 25, thereby moving actuating bar 22 and links 20 and 21 to open or close all three dampers 18. A single control, therefore, suffices to move all three, or any other multiple of, dampers 18 to the same extent, permitting all of them to be opened or closed simultaneously.

Referring now to Figures 2, 3, 4 and 8, at each end of the ventilator the end structure includes, for each ventilating channel or element, a pair of end panels, sometimes also called main braces, designated 31 and 32. Panels or braces 31 and 32 are mirror images of each other, see Figure 4, wherein they are shown as removed from the other parts of the ventilator but in their working relation to each other. Each brace or panel has a plurality of integrally turned stiffening and attaching flanges 80, 81, 82, 83 and 84 all of which contribute to the strength and stiffness of the panel and all the flanges except 82 being appropriately apertured to facilitate attachment between the panels and other parts of the ventilator as with bolts and nuts or sheet metal screws, for example; the flanges 80 being secured to and supporting side walls and partitions 5, 6, 7 and 8, Figs. 2, 3 and 8, the flanges 81 being secured to and resting upon ends of the lower troughs and the supporting flanges F of the apron 4, Figs. 6, 7 and 8, and flanges 83 and 84 carrying and/or affording attachment with top gutters 33 and ridge baffles 36 and 37 as will appear more fully below.

Referring now to Figures 3, 7 and 8, the apron 4 on the upper portions of each of the inclined edges of the trapezoidal portions 11, 12 and 13 has an integrally formed outwardly turned apertured flange F complementarily juxtaposed to and for supporting attachment with the flanges 81 of the braces 31 and 32; the lower troughs resting on the "notches" in and flanges F of the apron and the braces in turn resting on the troughs directly above the flanges. Appropriate bolts, not shown, passing through aligned apertures in the troughs and flanges with nuts, not shown, for securing the parts together, Figs. 2 and 8. The lower horizontal edges of the braces 31 and 32 are spaced above the lower portions of the troughs and half troughs 14-17 to permit the

free overflow of rain or other effluent from the troughs and half troughs outwardly over and beyond the apron 4 and to spill over and away from the apron and away from the damper operating linkage, see also Figure 6. The pairs of braces overlying the full troughs 14 and 15 engage the partitions 6 and 7 between their flanges 80 and are secured to each other and to the partitions through aligned apertures and bolts and nuts or equivalent attaching means; the several parts coacting advantageously to give a strong and stiff structure.

While it is not shown in the drawings I prefer to provide and secure braces 31 and 32, not only at the ends of the ventilator and troughs, gutters, baffles, partitions and walls thereof but also in the mid-portion or mid-length thereof and secure the same in the same way and in the same relation to the associated parts except the apron which, per se, does not traverse the mid-length of the ventilator. The braces in the mid-portion of the ventilator are carried by the troughs, gutters, wall, partitions and baffles to which they are attached and secured and serve to strengthen and stiffen the whole structure and also function aerodynamically as transverse baffles tending to reduce eddying and cross-currents of air in the ventilator.

Extending from end to end of the ventilator above the throat and damper of each element, see Figs. 2, 3 and 5, are upper gutters or troughs 33 carried by the braces 31 and 32 and particularly the flanges 83 thereof to which they are secured. Each gutter 33 has two laterally extending downwardly inclined flanges 34 and 35 provided with vertical lips 34a and 35a, Figure 5, such flanges overlying marginal flanged portions 14c, 15c, 16c and 17c of the bottom gutters. Preferably flanges 34 and 35 make an angle of about 30° to the horizontal, respectively paralleling the slope of the subjacent bottom gutters; both upper and lower troughs or gutters having their main parts sloping at an angle of about 30° to the horizontal. The ends of all three center gutters 33 are lipped as at L', Figures 3 and 6 and extend outwardly beyond the braces 31 and 32 and the lipped ends of the top gutters 33 immediately overlie splash plates 44, Figs. 2 and 6, to spill water outwardly beyond and away from the throats and dampers.

Gutters 33 carry off rain water, which they receive directly and discharge at the two opposite ends of the ventilator. In one sense they may be considered as deck structure overlying the throats and dampers 18 of each element and diverting rain, sleet, snow, etc. therefrom. It will be noted that the central bottom portions of center gutters 33 are preferably flattened to conserve height and are disposed closely adjacent the edge portions 18a of dampers 18 when the latter are in vertical position; this being indicated by the locus defined by the upper of the two dotted arrows in Figure 5. In terms of the height of the element and unit the bottom of the gutter 33 is located approximately half the damper width above the axis 19, i. e. about half the throat width (plus the overlap of the damper) above the throat. The extreme side edges of the gutter 33 being somewhat higher than the bottom middle thereof, the outlet air passages between the upper flanges of the lower troughs and the lower edges of the vertical lips 34a and 35a of the upper trough are preferably a little greater than half the width of the throat and facilitate the free flow of air and gases therebetween. The flat bottoms of the gutters taken with the shallow (preferably 30°) slope of the sloping sides and the flatness of the reversed slope of the flanges 34 and 35 all collectively contribute to reducing the height of the ventilator. As will presently appear the remaining upward and outward passage for air and gases as they flow around and above the edges of the side flanges of the troughs 33 become very much larger than half the throat opening and greatly facilitate air and gas movement in a novel and advantageous way; the extreme edges of the gutters 33 being spaced from the walls and partitions 5, 6, 7 and 8 not

less, and preferably somewhat more, than half the width of the throat, the net horizontal displacement of the gutters to the throat affording approximately no less than the rule of thumb 40% net ventilating opening.

At each of the two opposite ends of the ventilator, three splash shields 44, Figures 2 and 6, which at their upper portions conform in shape to the shape of center gutter 33, but otherwise are generally rectangular, complete the end wall structure. Each such splash shield is mounted outwardly of and secured to braces 31 and 32 in the position indicated in Figure 2 and preferably secured thereto by bolts and nuts not shown. Each splash plate has its upper edge underlying the lipped end of a gutter 33 and each splash plate closes the opening O, Fig. 3, defined by the juxtaposed end plates 31 and 32 above the throat and damper and below the top gutter, and each splash plate overlaps the upper inner portions of the lower troughs and half troughs and overlies the end of each adjacent damper and is spaced from the proximate end of the adjacent damper shaft 19 and terminates in a 20 straight horizontal lower edge below the straight adjacent upper edges of the apron 4, the damper axis and the throat whereby to exclude the spill from gutter 33 from the throat and damper and the damper rod and bearing B therefor in the apron. The openings O between the braces 31 and 32 are at least at their upper parts as wide as the gutters 33 to admit longitudinal insertion or removal of the gutters therethrough when the splash plates are not attached; the gutters preferably being secured to and under the flanges 83 of the braces by bolts and nuts or equivalents. When the gutters 33 and splash plates are joined and secured to the braces 31 and 32 continuous load bearing end walls for the ventilator are completed and a continuous interconnected mutually bracing and supporting strong and stiff structure is afforded from and with the apron, braces, wall partitions and gutters or troughs.

Flanking each gutter 33 from end to end thereof and in part rising above and overlying the flanges 34 and 35 of the gutters are laterally opposed and downwardly and outwardly directed deflecting panel means 36 and 37 hereinafter sometimes called ridge baffles. As best appears in Fig. 5, in the preferred form of my invention these ridge baffles are more or less gambrelled in shape, each comprising an upper vertical portion 38 or 39, an intermediate slant portion 40 or 41, and a lower vertical portion 42 or 43, as the case may be. Slant portions 40 and 41 respectively, lie substantially parallel to directing flanges 34 and 35 of gutters 33 and are spaced upwardly and outwardly therefrom; the slants 40 and 41 being considerably longer than the directing flanges 34 and 35, thereby facilitating the disposition of the upper vertical portions 38 and 39 of the ridge baffles vertically above and in overlapping relation to the flanges 34 and 35 and the lower vertical portions 42 and 43 about midway between the lateral edges of the flanges 34 and 35 and the vertical walls and partitions 5, 6, 7 and 8. Ridge baffles 36 and 37 rest upon and are supported by and attached to the flanges 84 of the panels or braces 31 and 32 respectively, preferably through properly aligned apertures and attaching means and the ridge baffles preferably overlie slightly the end panels 31 and 32 at the flanges 84, the panels being notched at 31a and 32a to accommodate the lower vertical portions 42 and 43 when the parts are assembled and secured together. It will also be noted that the lower ends of the ridge baffles 36 and 37 terminate well below the level of the uppermost portions of center gutter 33, and, more importantly, below the straight broken lines r drawn from the upper edges of the partitions 6 and 7 to the upper edges of the flanges 14c and 15c at the throat wherewith to intercept and deflect driving rain from entering the throat opening. The lowermost edges of gambrel baffles 36 and 37 may depend somewhat lower than illustrated in Fig. 5 without impairing the aerodynamics of my ventilator and with corresponding increased weatherproof-

ness. I prefer the depth and disposition shown for most purposes since it affords weatherproofness and aerodynamic efficiency with the use of a modest amount of material.

As further appears from Figures 2 and 5, the upper portion of each ventilating element may be considered as being divided into an outer passage A adjacent side wall 6, an outer passage B adjacent side wall 7 and a wide center passage C between the ridge baffles 36 and 37. Passages A and B are of maximum width at the top of the ventilator, of progressively decreasing width in the vicinity of slants 40 and 41, and of minimum width near the lower portions 42 and 43 of gambrels 36 and 37. Passage C is of minimum width between upper vertical portions 38 and 39, of greater width between slants 40 and 41, and of maximum width between lower vertical portions 42 and 43. Abreast the directing flanges 34 and 35 of gutter 33, passage C may be considered as branching into two like passages D and E of about the same width as the lower end of passages A and B. The combined areas of the lower end of passage A and passage D and the lower end of passage B and passage E being, as mentioned above, of no less area than the area of the throat opening.

With the dampers in open, i. e. vertical, position upwardly moving air and gases have a novel easy path of flow from the throat to and out of the top of the ventilator; the path in its rightward and leftward, as viewed in Fig. 5, outer portions inclining upwardly and outwardly on smooth gentle curves to proximity with the vertical walls or partitions and then continuing vertically with increasing area in the passages A and B. The inner portions of the path of outflowing gases while probably following compound curves from adjacent the damper through D and into C have the desirable characteristics of much verticalness in relation to horizontalness and increasing area from the throat to the ultimate outlet at C. It may also be appreciated that prior practice has generally confined the ultimate outlet to the size and disposition of the outlet C, whereas I have substantially doubled the outlet area by adding the passages A and B. Moreover my invention provides straight vertical walls at and throughout the whole outlet area as by the upper portions of partitions and the vertical portions 38 and 39 of the ridge baffles or gambrels with an improved education effect from outside air movement.

It may also be appreciated that these enhanced aerodynamic qualities have been companion to a decrease in overall height of the ventilator as evidenced by the vertical proximity between the slants 40 and 41 of the ridge baffles and the flanges 34 and 35 of the top gutters, which proximity is obtained because the passage therebetween need accommodate but approximately half the outflowing gases, whereas prior practice required passages in this place to accommodate all the outflowing gases. This advantage has been such that my invention gives both a reduced height of the whole ventilator and significant vertical lengths 38 and 39 of the ridge baffles.

By relating and proportioning the parts in substantially the manner shown, wind-swept rain coming as if from the upper left-hand or upper right-hand corner of any ventilating element as viewed in Figure 5 will be deflected by the baffles or gambrels 36 and 37 and taken by gutter 33 without getting an opportunity to enter the throat. Having been deflected by gambrels 36 and 37 and/or gutters 33, as the case may be, wind-swept rain entering the ventilator will be caught and carried away by the top gutters and bottom gutters and half gutters. Rain falling vertically is similarly caught and discharged without opportunity to enter the throats of the ventilating elements or units.

My ventilator also comprises end cap or closure constructions 9 at each end thereof, Figures 1 and 6, carried by end braces 31 and 32 and spaced from and enclosing, inter alia, the open ends of the gutters and half gutters. As shown in Figures 2, 3 and 6 there is an upper series of

mounting brackets 45 and a lower series of mounting brackets 46, each of such mounting brackets being more or less U-shaped with their flanged "feet" secured to the panels 31 and 32 and the base parts of the U affording supporting attachment for upper and lower portions respectively of the caps 9. It will be observed that mounting brackets 45 are somewhat shallower than mounting brackets 46 to facilitate the somewhat greater spacing of the lower portions of the caps from the end panels and inner end wall structure.

As appears from Figures 1 and 6 of the drawings, end cap 9 at the near end of the ventilator as seen in Figure 1 comprises two principal upper and lower parts, 9a and 9b respectively. The upper part 9a includes a vertically extending portion 50 disposed closely adjacent the upper part of the end wall structure of the ventilator with an inwardly extending horizontal flange 51 overlying the ends of the upper edges of the walls, partitions and ridge baffles. Below portion 50 part 9a has an outwardly directed slant 52 which offsets the lower vertical portion 53 of the upper half of the end cap 9 to an extent sufficient to permit substantially unobstructed discharge of rain water from top gutters 33. At its bottom, lower vertically extending portion 53 is provided with an upwardly turned open lip 54, best seen in Figure 6. The upper half 9a of end cap 9 is held in place on the ventilator by means of brackets 45, to which it is affixed by convenient means such as nuts and bolts.

Cooperating with the upper half of end cap 9 is the detachable lower half 9b provided at its upper edge with a complementary but downwardly extending open lip 55. By means of lips 54 and 55 the detachable lower half of end cap 9 can be hooked onto the stationary upper half of end cap 9. Below lip 55 the detachable lower half of end cap 9 has a vertically extending portion 56 which terminates in an inward slant 57 that begins abreast the bottom gutters and half gutters and is directed toward but terminates spaced from apron 4, Figure 6. Slant 57 carries at its bottom a second vertically extending portion 58 which terminates preferably below the top of curb 2 outwardly of apron 4. The detachable lower half of end cap 9 is held in place on supporting brackets 46 by quick-detachable means such as bolts and wing nuts 59 and therefore is readily removable from the upper half and from the ventilator as a whole. As shown in Figure 1, side pieces 60 and 61, respectively, close the side ends of the end caps.

The "quick detachability" of the lower portions 9b of the end caps 9 facilitates cleaning, adjustment, inspection and repair especially of the lower and moving and actuating parts of the ventilator. With little extra trouble the upper half 9a may also be removed for less usual inspections, painting and/or repair of the parts adjacent to it. The end caps when positioned enhance the appearance of the ventilator, close the ends of the ventilator aerodynamically, contain and direct the outflow of water and discharge from the gutters and prevent the ingress of undesirable material and elements into the ends of the ventilator.

The foregoing description has been largely confined to my preferred form of a ventilator "unit" comprising three ventilating elements, each characterized by one throat and damper, and it will be appreciated that the units and elements may be multiplied to any desired extent essentially by substituting a partition 6 or 7 for one of the end walls 5 or 8, repeating the structure of panels, braces, gutters and baffles and extending or splicing the apron, caps and linkages in known and practicable ways, all this while retaining and correspondingly multiplying the advantages and benefits of the principle of my invention. While I have illustrated and described a preferred form of my invention, changes, modifications and improvements will occur to those skilled in the art who come to understand my teaching and enjoy the advantages of my invention, and therefore I do not wish to be limited in the scope of

my patent to the form of my invention herein specifically disclosed to illustrate and exemplify the same nor in any manner inconsistent with the promotion of progress in the art marked by my invention.

I claim:

1. In a gravity roof ventilator for a roof opening defined by an upstanding curb, a vertical apron surrounding the exterior of said curb and extending vertically from below the top of the curb to a level above the top of the curb, brackets resting on the top of the curb carrying said apron, said apron having notches in its upper edge and flanges turned normal to the apron at said notches, drain trough members disposed in said notches and spanning said roof opening and extending beyond said apron, vertical braces rising from said trough members above said apron and, with said trough members, secured to the said flanges of the apron, dampers having axes journaled in said apron between said trough members, gutters disposed above said dampers and carried by said braces and extending at their ends outwardly away from said roof opening beyond said braces and apron, vertically rising baffles standing above said trough members and between said gutters and carried by said braces, gambrelled baffles carried by said braces and extending between said vertical baffles and said gutters and overlapping the edges of said gutters, splash plates carried by said braces with the upper edges traversing and underlying the said ends of said gutters and their lower edges overlying the ends of said trough members and spaced from the ends of said dampers and spaced from said apron, damper actuating mechanism disposed between the planes of said apron and said splash plates, brackets carried by said braces extending outwardly beyond the ends of the trough members and gutters, and caps carried by said brackets and spaced from and overlying the ends of said gutters and trough members and having inturned flanges overlying the upper edges of said baffles.
2. In a gravity roof ventilator for a roof opening defined by an upstanding curb, a vertical apron surrounding the exterior of said curb and extending vertically from below the top of the curb to a level above the top of the curb, brackets resting on the top of the curb carrying said apron, said apron having notches in its upper edge and flanges turned normal to the apron at said notches, drain trough members spaced apart and disposed in said notches and spanning said roof opening and having upper side edges defining throats therebetween and extending beyond said apron, vertical braces rising from said trough members above said apron and, with said trough members, secured to the said flanges of the apron, gutters having upwardly and outwardly inclined sides and side edges and being disposed above said throats with the respective edges of said gutters vertically spaced from and overlapping the respective adjacent edges of said trough members and carried by said braces and extending at their ends outwardly away from said roof opening beyond said braces and apron, vertically rising baffles standing above said trough members and between said adjacent gutters and exteriorly of the outermost gutters and carried by said braces, gambrelled baffles carried by said braces and extending between said vertical baffles and said gutters and overlapping the edges of said gutters, splash plates carried by said braces with the upper edges traversing and underlying the said ends of said gutters and their lower edges overlapping the ends of said trough members and spaced from the ends of said throats and spaced from said apron, brackets carried by said braces extending outwardly beyond the ends of the trough members and gutters, and caps carried by said brackets and spaced from and overlying the ends of said gutters and trough members and having inturned flanges overlying the upper edges of said baffles.
3. In a gravity roof ventilator for a roof opening defined by an upstanding curb, a vertical apron surrounding the exterior of said curb and extending vertically from

below the top of the curb to a level above the top of the curb, brackets resting on the top of the curb carrying said apron, said apron having notches in its upper edge and flanges turned normal to the apron at said notches, drain trough members disposed in said notches and spanning said roof opening and extending beyond said apron and having upper side edges, vertical braces rising from said trough members above said apron and, with said trough members, secured to the said flanges of the apron, dampers having axes journalled in said apron between said trough members, gutters having upwardly and outwardly inclined sides and side edges and being disposed above said dampers with the respective edges of said gutters vertically spaced from and overlapping the respective adjacent edges of said trough members and carried by said braces and extending at their ends outwardly away from said roof opening beyond said braces and apron, vertically rising baffles standing above said trough members and between said adjacent gutters and exteriorly of the outermost gutters and carried by said braces, gambrelled baffles carried by said braces and extending between said vertical baffles and said gutters and overlapping the edges of said gutters, splash plates carried by said braces with the upper edges traversing and underlying the said ends of said gutters and their lower edges overlapping the ends of said trough members and spaced from the ends of said dampers and spaced from said apron, and damper actuating mechanism disposed between the planes of said apron and said splash plates.

4. In a gravity roof ventilator for a roof opening defined by an upstanding curb, a vertical apron surrounding the exterior of said curb and extending vertically from below the top of the curb to a level above the top of the curb, brackets resting on the top of the curb carrying said apron, said apron having notches in its upper edge and flanges turned normal to the apron at said notches, drain trough members spaced apart and disposed in said notches and spanning said roof opening and defining throats therebetween and extending beyond said apron, vertical braces rising from said trough members above said apron and, with said trough members, secured to the said flanges of the apron, gutters having upwardly and outwardly inclined sides disposed above said throats and carried by said braces and extending at their ends outwardly away from said roof opening beyond said braces and apron, vertically rising baffles standing above said trough members and between said adjacent gutters and exteriorly of the outermost gutters and carried by said braces, gambrelled baffles carried by said braces and extending between said vertical baffles and said gutters and overlapping the edges of said gutters, and splash plates carried by said braces with the upper edges traversing and underlying the said ends of said gutters and their lower edges overlapping the ends of said trough members and spaced from the ends of said throats and spaced from said apron.

5. In a gravity roof ventilator for a roof opening, an apron surrounding said roof opening and having spaced notches in its upper edge and flanges turned normal to the apron at said notches, drain trough members disposed in said notches and spanning said roof opening and defining throats therebetween and extending beyond said apron, vertical braces rising from said trough members above said apron and, with said trough members, secured to the said flanges of the apron, gutters having upwardly and outwardly inclined sides disposed above said throats and carried by said braces and extending at their ends outwardly away from said roof opening beyond said braces and apron, vertically rising baffles standing above said trough members and between said adjacent gutters and exteriorly of the outermost gutters and carried by said braces, gambrelled baffles carried by said braces and extending between said vertical baffles and said gutters and overlapping the edges of said gutters, and splash

plates carried by said braces with the upper edges traversing and underlying the said ends of said gutters and their lower edges overlapping the ends of said trough members.

5. In a gravity roof ventilator for a roof opening, an apron adapted to surround the said roof opening and having spaced notches in its upper edge, spaced drain trough members disposed in said notches and defining throats therebetween and extending beyond said apron, vertical braces rising from said trough members above said apron, gutters having upwardly and outwardly inclined sides disposed above said throats and carried by said braces and extending at their ends outwardly beyond said braces and apron, vertically rising baffles standing above said trough members and between said adjacent gutters and exteriorly of the outermost gutters and carried by said braces, gambrelled baffles carried by said braces and extending between said vertical baffles and said gutters and overlapping the edges of said gutters, and splash plates carried by said braces with the upper edges traversing and underlying the said ends of said gutters and their lower edges overlapping the ends of said trough members and spaced from the ends of said throats and spaced from said apron.
7. In a gravity roof ventilator for a roof opening an apron adapted to surround said roof opening and having spaced notches in its upper edge, spaced drain trough members disposed in said notches and spanning said roof opening and having upper side edges defining throats therebetween, vertical braces rising from said trough members above said apron, gutters having upwardly and outwardly inclined sides and side edges and being disposed above said throats with the respective edges of said gutters vertically spaced from and overlapping the respective adjacent edges of said trough members and carried by said braces and extending at their ends outwardly away from said roof opening beyond said braces and apron, vertically rising baffles standing above said trough members and between said adjacent gutters and exteriorly of the outermost gutters and carried by said braces, and splash plates carried by said braces with the upper edges traversing and underlying the said ends of said gutters and their lower edges overlapping the ends of said throats.
8. In a gravity roof ventilator for a roof opening an apron adapted to surround said roof opening and having spaced notches in its upper edge at opposite sides of said opening, spaced drain trough members disposed in said notches and spanning said roof opening and extending beyond said apron and having edges defining throats therebetween, vertical braces rising from said trough members above said apron, gutters having upwardly and outwardly inclined sides and side edges and being disposed above said throats with the respective edges of said gutters vertically spaced from and overlapping the respective adjacent edges of said trough members and carried by said braces and extending at their ends outwardly away from said roof opening beyond said braces and apron, vertically rising baffles standing above said trough members and between said adjacent gutters and exteriorly of the outermost gutters and carried by said braces, splash plates carried by said braces with the upper edges traversing and underlying the said ends of said gutters and their lower edges overlapping the ends of said trough members and spaced from the ends of said throats, brackets carried by said braces extending outwardly beyond the ends of the trough members and gutters, and caps carried by said brackets and spaced from and overlapping the ends of said gutters and trough members.
9. A roof ventilator comprising a plurality of parallel substantially horizontal lower gutter elements spaced apart and defining a ventilating throat opening therebetween, an upper gutter overlying said throat opening and in part overlapping said lower gutter elements and being spaced thereabove and defining outlet passages of

not more net restriction than said throat openings, vertical baffles disposed above said lower gutter elements and rising from below the throat opening and defining outlet passages beside said upper gutter no smaller than said throat opening, auxiliary baffles rising from between said upper gutter and said vertical baffles to points overlying the edges of said upper gutters and spaced therefrom, means for closing the ends of the throat opening, means for diverting liquid from said upper gutter from the throat opening and means for supporting the gutter, gutter elements and baffles in fixed spacial relation.

10. A gravity roof ventilator comprising supporting structure adapted to be mounted on a roof over a roof opening, laterally opposed drainage members on the lower portion of the structure having outwardly and downwardly sloping surfaces and opposed edges defining a central throat opening for the upward passage of air and gases, vertically extending substantially straight side walls laterally spaced from and rising from below the plane of said throat opening, the upper ends of said side walls defining the width of the exhaust opening of said ventilator, means carried by said structure and carrying said side walls, a longitudinally extending gutter member disposed centrally of said throat opening intermediate said exhaust and throat openings, the vertical spacing between said gutter member and said throat opening and the lateral spacing between the side walls and the lateral edges of said gutter member each providing passage for said air and gases of no less area than said throat, said means supporting said gutter, laterally spaced vertically extending baffles supported on said means and rising substantially from the horizontal plane of the lateral edges of the gutter member and from between and being spaced from the adjacent side wall and edge of the gutter member and intersecting a straight line between the top of the side wall and the edge of the gutter member, said baffles being adapted to prevent the elements from passing over said side walls and through said vertical spacing between said gutter member and said throat opening, and end wall means carried by said means and extending transversely of said gutter member at the ends thereof and protecting the ends of said throat opening from the elements.

11. A roof ventilator comprising, in combination, a plurality of parallel lower trough members having upper side edges approximately in a horizontal plane and spaced apart and defining throat openings therebetween, a plurality of parallel upper trough members having greater width than said throat openings and spaced apart and each overlying a throat opening and vertically spaced thereabove a distance no less than half the width of said throat openings, baffle members extending parallel to said trough members above said lower trough members and between said upper trough members, means supporting said members in spaced relation to each other, means for draining water from said troughs, and means for closing the ends of said throat openings and for preventing water from entering the ends of the throat openings.

12. The ventilator of claim 11 in which certain of said baffle members extend below said throat openings and others of said baffle members overlie the side edges of said upper trough members.

13. A roof ventilator comprising a plurality of parallel, longitudinally extending, substantially horizontal lower trough members having upper side edges approximately in a horizontal plane and being spaced apart and defining throat openings therebetween, gutters having

side edges disposed above and vertically spaced from said throat openings, vertically rising baffle members standing above said lower trough members and rising between each pair of adjacent gutters and exteriorly of each of the outermost gutters, auxiliary baffle members rising from above said lower trough members, and between the respective edges of said gutters and adjacent vertically rising baffles and having upper portions thereof vertically spaced from and overlapping said respective edges of said gutters, means for supporting said members in fixed spacial relationship, and means for draining said trough members away from said throat openings.

14. A roof ventilator for a roof opening comprising, in combination, a plurality of parallel approximately level lower trough members having upper edges approximately in a horizontal plane and spaced apart and defining throat openings therebetween for gases entering the ventilator from said roof opening, a plurality of parallel approximately level upper trough members spaced apart no less than the width of said throat openings and having greater width than said throat openings and each overlying a throat opening and excluding vertically falling rain therefrom and vertically spaced thereabove a distance no less than half the width of said throat openings, baffle members extending parallel to said trough members above said lower trough members and between said upper trough members and excluding diagonally falling rain from said throat openings, all said members being formed and spaced from and related to each other to define therebetween substantially continuously upwardly inclined paths for gases flowing from said roof opening through the ventilator and of substantially increasing cross-sectional area from said throat openings and with gentle changes in direction conducive of non-turbulent flow through the ventilator, means supporting said members in spaced relation to each other, means draining water from said troughs, and means for diverting water away from the said roof opening.

15. The ventilator of claim 11 in which certain of said baffle members extend below said throat openings.

16. The ventilator of claim 11 in which said upper trough members have side edges and certain of said baffle members have portions which overlie and are vertically spaced from the adjacent side edge.

17. The ventilator of claim 11 in which said upper trough members have lateral edges and certain of said baffle members rise to a greater height than the adjacent lateral edges of said upper trough members and certain other of said baffle members are disposed between each said edge of said upper trough members and adjacent first baffle member and intersect all straight lines between the top of said adjacent first baffle member and the space between said edge and the adjacent upper side edge of said lower trough members.
